United States Patent Office

Des. 218,888
Patented Oct. 6, 1970

218,888

CUSHION

John E. Blank, Grand Rapids, Mich., assignor to Group Seven, Inc., Grand Rapids, Mich., a corporation of Michigan

Filed May 14, 1969, Ser. No. 17,149

Term of patent 14 years

Int. Cl. D6—01

U.S. Cl. D15—8

FIG. 1.

FIG. 2.

FIG. 4.

FIG. 5.

FIG. 3.

FIG. 1 is a perspective view of a cushion according to the invention;

FIG. 2 is a side elevational view thereof;

FIG. 3 is a top or plan view thereof;

FIG. 4 is a front view thereof; and

FIG. 5 is a back view thereof.

The side of the article not shown is a mirror image of the side shown.

I claim:

The ornamental design for a cushion, as shown and described.
